SMOKER'S STAND

Samuel Cohen, Montreal, Quebec, Canada

Application November 25, 1953, Serial No. 27,786

Term of patent 7 years

(Cl. D85—2)

To all whom it may concern:

Be it known that I, Samuel Cohen, of 5975 Wilderton Avenue, Montreal, Province of Quebec, Canada, have invented a new, original, and ornamental Design for a Smoker's Stand, of which the following is a specification, reference being had to the accompanying drawing, forming part thereof, and wherein:

The single figure is a perspective view of a smoker's stand, showing my new design.

The side of the stand not shown has substantially the same appearance as the side shown in the single figure.

I claim:

The ornamental design for a smoker's stand, as shown and described.
